HAND BRAKE

Staey B. Haseltine, Chicago, Ill., assignor to
W. H. Miner, Inc., Chicago, Ill., a corporation
of Delaware

Application February 21, 1930. Serial No. 430,187

18 Claims. (Cl. 188—81.1)

This invention relates to improvements in hand brakes.

One object of the invention is to provide a simple and efficient hand brake mechanism, wherein all of the operations necessary to apply and release the brakes are effected by a single manually operated member, operation of which in one direction effects tightening of the brakes and in a reverse direction effects release of the same, and wherein means is provided for holding the brakes in tightened condition, which means is automatically rendered operative when the manually operated member is actuated in a tightening direction, and is automatically thrown to inoperative position when the manually operated member is actuated in a reverse direction to effect release of the brakes.

A more specific object of the invention is to provide a hand brake mechanism including a chain winding drum and means for rotating the drum in one direction to tighten the brakes and in a reverse direction to release the same, together with means for preventing retrograde rotation of the winding drum, wherein the last named means is withdrawn from operative holding relation by movement of the rotating means in a direction to unwind the chain from the drum, and is automatically thrown into operative holding relation by movement of the rotary means in chain winding direction.

A further object of the invention is to provide a brake mechanism as specified in the preceding paragraph, wherein the operations of disengaging the holding means and effecting operative reengagement thereof with the chain winding means are performed without destroying the operating relation between the means for rotating the drum and the drum.

Another object of the invention is to provide in a brake mechanism of the character indicated including means for preventing retrograde rotation of the chain winding drum wherein all the operations of the brake mechanism are controlled by a single actuating member, and wherein the actuating member is at all times operatively connected with the chain winding drum, means for preventing accidental operation, through the pull of the brake chain, of the means for preventing rotation of the chain winding drum while the brake mechanism is being released.

Other objects of the invention will more clearly appear from the description and claims hereinafter following.

55 In the drawing, forming a part of this speci-

fication, Figure 1 is a front elevational view, partly in section, of my improved hand brake mechanism illustrating the same applied to the vertical end wall of a railway car and corresponding to the line 1—1 of Figure 2. Figure 2 is a vertical, transverse, sectional view corresponding substantially to the line 2—2 of Figure 1. Figure 3 is a view of the upper part of the brake mechanism, the view being a section similar to Figure 1 but showing the parts in a different position. And Figure 4 is a detailed, vertical, sectional view through the locking dog, latching cam and operating shaft of my improved hand brake mechanism, similar to Figure 3 but illustrating the parts in a slightly different position, and with the teeth of the gear D omitted.

In said drawing, 10 designates the end wall of a railway car on which my improved hand brake mechanism is mounted. The operating parts of the brake mechanism are preferably contained in a housing secured to said end wall. As shown in Figures 1 and 2, the housing comprises a rear section 11 in the form of a plate member, and a front section 12 in the form of a cover. The rear section 11 is of generally rectangular outline and has an inwardly offset wall portion 112, which is spaced from the end wall 10 of the car. The cover section 12 of the housing has lateral flange members 13—13 and an upstanding top lug member 14 by which the same is secured to the section 11. The two sections are secured together by a plurality of rivets 15—15 extending through the flange sections 13 and the lug 14 of the cover member 12, and through the corresponding portions of the rear section 11. The rivets 15 at the top and bottom of the housing are preferably also employed to secure the housing to the end wall 10 of the car and extend through said end wall, as clearly shown in Figure 2. The housing section 12 is open at the bottom, as indicated at 16, to accommodate the brake chain 17, which is connected to the operating parts of the brake mechanism proper of the railway car, not shown. The section 12 of the housing has a top wall 18 and side walls 19—19. At the top, the housing section 12 is provided with a vertically disposed front wall 20 spaced from the section 11, which forms the back wall of the housing, a sufficient distance to accommodate certain of the operating parts of the hand brake mechanism. Below the wall portion 20, the outer wall of the section 12 is outwardly offset, as indicated at 21 and clearly shown in Figures 1 and 2, to provide an enlarged 110

chamber portion to accommodate the chain winding drum of the brake mechanism.

My improved hand brake mechanism proper comprises broadly a chain winding drum A; 5 a gear B fixed to the drum; a rotary operating shaft C, which is guided for limited reciprocating movement; a pinion D fixed to the operating shaft; a hand wheel E; a locking dog F for preventing retrograde rotation of the chain winding 10 drum; and a latching cam G.

The chain winding drum A is supported for rotation on a shaft 22 having its opposite ends supported in openings 23 and 24 provided in the front and rear walls of the housing, respectively.

15 As clearly shown in Figure 2, both of these openings are suitably reinforced to strengthen the support for the shaft. The chain winding drum is of substantially conical form and has a helical winding groove 123 thereon. The inner end of 20 the brake chain 17 is connected to the winding drum A by means of a retaining pin, 124 extending through the end link of the chain and alined openings in the chain winding drum. The end link of the chain is accommodated in 25 a suitable recess 25 provided in that portion of the drum which is of largest diameter. The gear B, which is of considerably larger diameter than the winding drum A is formed integral therewith and is disposed on the inner side of 30 said drum. As shown in Figure 2, the locking pin 124, which serves to secure the chain to the drum also extends through the gear B. In order to prevent rotation of the supporting shaft 22, the outer end of the same is cut away at 35 one side to provide a flattened portion 26 which engages a similar flattened wall portion of the opening 23.

The operating shaft C extends through the upper part of the housing, and is accommodated 40 for reciprocating movement transversely of said housing within alined guideways or openings 27 and 28 provided in the front and rear walls of the housing, respectively. The shaft C is provided with a head 29 at the inner end thereof 45 which is accommodated between the offset wall portion 112 of the rear section of the housing and the end wall 10 of the car. The shaft C is cut away at one side as clearly shown in Figures 1, 3 and 4 to provide a flattened portion 30. 50 At the outer end, the shaft C carries the hand wheel E, which is fixed to the same, the hub of the hand wheel being provided with an opening of a cross section corresponding to that of the shaft to fit the same. The hand wheel E is secured by the usual locking nut 31 provided 55 at the outer end of the shaft C. The hub section of the hand wheel E fits between the top and bottom walls of the guideway 27 of the front wall of the housing and serves as the bearing member for rotatably supporting the front end 60 of the shaft C. At the outer end the hub of the hand wheel E, that is where the hub connects with the spokes thereof, the same is enlarged so as to provide an annular flange-like portion of such a size as to overlap and close the slot 32 in all operative positions of the hand wheel to prevent entry of foreign matter.

The pinion D is mounted on the shaft C between the head 29 thereof and the hub portion 70 of the hand wheel E. As shown, the pinion D is provided with laterally extending hub sections 32 and 33 on opposite sides thereof, which sections correspond in diameter to the diameter of the hub portion of the hand wheel E. The teeth 75 of the pinion D are located between the two

hub sections, the hub section 33 being accommodated for rotation between the top and bottom walls of the guide slot 28 in the rear section 11 of the housing. The slots 27 and 28 are so located with respect to the gear B, that the 80 pinion D will at all times mesh with the teeth of the gear B while the pinion is guided for reciprocating movement.

The locking dog F is pivotally supported by means of a pin 34 at a point above the pinion D. As shown, the locking dog F has a section 85 35 disposed above the pinion and a depending portion 36 at the outer end thereof extending past the pinion and having a tooth 37 at the extremity thereof cooperating with the teeth of 90 the gear B in order to prevent retrograde rotation of the chain winding drum. The locking dog F is provided with a pair of spaced flanges 38—38 at the inner side of the sections 35 and 36, said flanges 38—38 spanning the gear teeth 95 of the pinion D and being adapted to be engaged by the hub sections 32 and 33 at opposite sides of said pinion.

The locking cam G is in the form of a casting pivotally supported by a pivot pin 39 immediately below the pivot 34 of the locking dog F. This latching cam G has spaced flanges 40—40 at the lower side thereof, as viewed in Figure 1, the flanges extending upwardly along the lefthand side of said member, as viewed in 105 said figure. The flanges 40—40 are spaced apart such a distance as to span the teeth of the pinion D and gear B and are adapted to be engaged by the hub portions 32 and 33 of said pinion. The flange sections 40—40 of the member G 110 form cam members cooperating with the hub portions of the pinion. As most clearly illustrated in Figure 1, the combined latching and cam member G is cut away at the inner side immediately above the pivot member thereof, 115 as indicated at 41, to accommodate the pivot portion of the locking dog F. Immediately adjacent the cut away portion 41, the flanges 40—40 of the member G are provided with a downwardly inclined cam portion 42, as seen 120 in Figure 1, which when said member G is rotated in a righthand direction, as viewed in Figure 1, will engage beneath the pivoted portion of the dog F to cam the same upwardly, as hereinafter more clearly pointed out. Immediately 125 adjacent the cam portions 42—42, the flanges 40 are provided with substantially vertical portions 43—43 which are notched, as indicated at 44, to conform to the hub portions 32—33 of the pinion D, and have the hub portions 130 seated therein, when the parts are in the position as shown in Figure 1. Immediately beneath the cam portions 44—44, the flange members 40—40 are provided with inclined cam faces 135 45—45 which are adapted to engage the hub sections 32—33 of the pinion D, when the pinion is in the extreme lefthand position, as shown in Figures 3 and 4. As will be evident, due to the weighted portion of the combined locking and cam member G being located above the pivotal axis of said member, the normal tendency is 140 for the member G to swing downwardly about said pivot.

The operation of my improved hand brake mechanism is as follows: In tightening or applying the brakes, assuming the parts to be in the position shown in Figure 1, the hand wheel E is rotated in a clockwise direction, thereby effecting rotation of the pinion D in a similar direction, the pinion intermeshing with the gear 145 150

B effecting rotation of the latter and the chain winding drum in a contra-clockwise direction, thereby winding the chain 17 on the drum. At this time, the locking dog F is free to operate and is urged toward the gear B through the action of gravity. During rotation of the gear B in a contra-clockwise direction, the dog ratchets over the gear teeth of the member B and locks with said teeth to prevent retrograde rotation of the drum, or rotation of the same and the gear B in a clockwise direction. Inasmuch as the operating shaft C is actuated in a clockwise direction, the pinion D will be held at the righthand ends of the guide slots 27 and 28, as viewed in Figure 1. At this time, the cam portions 44 of the member G are engaged by the hub sections of the pinion, thereby maintaining the member G in the position illustrated in Figure 1.

When it is desired to release the brakes, the operator rotates the hand wheel E in a contra-clockwise direction. Inasmuch as the gear B is locked against rotation in a clockwise direction by the locking dog F, the pinion D will be forced to travel along the gear teeth of the gear B toward the left, as viewed in Figure 1 to the position shown in Figure 3. During this movement of the pinion, the hub portions thereof by engagement with the flanges 38-38 of the dog raise the dog out of engagement with the teeth of the gear, as shown in Figure 3. As will be evident, during the movement of the pinion from the position shown in Figure 1 to that in Figure 3, the same is moved away from the combined latching and cam member G, and the latter is free and is urged by gravitation to swing about its pivot in a clockwise direction, as viewed in Figure 1, following the movement of the pinion until it reaches a position where the cam faces 42-42 thereof come into operative engagement with the bottom edge of the section 35 of the dog F, whereby movement of the member G is somewhat retarded. At this time, the cam faces 45-45 of the member G are in such a position as to engage the hub sections of the pinion and form stop means to limit movement thereof to the right, as viewed in Figure 3. At the instant the dog is freed from engagement with the gear B, as shown in Figure 3, the cam member G, which is in engagement with the bottom edge of the section 35 of the dog, by further swinging movement thereof in a clockwise direction, lifts the dog to further withdraw it so as to completely clear the teeth of the gear E. At the same time, the pull of the brake chain on the winding drum, through the gear B, will effect displacement of the pinion to the right as viewed in Figure 3 until arrested by the stop faces 45-45 of the cam G, as shown in Figure 4, and due to the pull of the chain the pinion will be held in a position hugging the cam surfaces 45-45. In order to limit the upward swinging movement of the dog, a stop member 50 is preferably provided, the same being in the form of a transverse rib on the housing. Further rotation of the pinion D in a contra-clockwise direction through operation of the hand wheel will effect rotation of the gear B in a clockwise direction so as to unwind the chain, the pinion D being maintained in the position shown in Figure 4 by engagement of the hub portions thereof with the stop or cam faces 45-45 of the member G, as hereinbefore pointed out. Unwinding of the chain may thus be controlled by the hand wheel, thereby permitting the brakeman to back

off the brakes in the usual manner. In this connection, it is pointed out that due to frictional engagement between the hub of the pinion and the faces 45-45 of the cam G, the tendency will be to rotate the latter in a clockwise direction, thereby tending to lift the dog F and maintain the same in engagement with the stop member 50. The cam member G will thus be maintained in holding position, while the pinion D is rotated in a contra-clockwise direction. When it is desired to completely release the brakes, the hand wheel E is released by the operator immediately after the dog F has been thrown out of engagement with the teeth of the gear B and the chain permitted to unwind through the pull thereof. Rotation of the gear B during this action will cause rotation of the pinion in a contra-clockwise direction, as viewed in Figures 3 and 4 and inasmuch as the hub members of the pinion are in frictional engagement with the cam surfaces 45-45 of the member G, the tendency of such frictional contact will be to rotate the member G in a clockwise direction, thereby maintaining the surfaces 45-45 thereof engaged with the hub portions of the pinion and holding the pinion in the position shown in Figure 4.

In again applying the brakes after the parts have been left in the positions shown in Figures 3 and 4, the hand wheel E is rotated in a clockwise direction, thereby rotating the pinion D in a clockwise direction also. Due to the frictional engagement between the pinion, hub sections and the surfaces 45-45 of the member G, the tendency will be to rotate the member G in a contra-clockwise direction about its pivot, thereby bringing the cam surfaces 44-44 opposite the hub sections of the pinion and permitting movement of the pinion to the right, as viewed in Figure 3, through engagement of the teeth thereof with the teeth of the gear B. The force exerted by engagement of the teeth of the pinion with the teeth of the gear B also aids in swinging the member G back to the position shown in Figure 1 by forcing said pinion to travel to the right in the guide slots 27 and 28. As the pinion travels to the right, as viewed in Figure 3, the hub sections thereof will move away from the flanges 38-38 of the dog F, thereby permitting the dog to swing downwardly toward the gear B. When the pinion reaches the position shown in Figure 1, the dog is in full engagement with the teeth of the gear B and the flanges 38-38 of the dog are entirely clear of the hub sections of the pinion, thereby permitting free oscillating movement of the dog to allow its ratcheting action in connection with the teeth of the gear B. As will be evident, swinging movement of the combined latching and cam member G from the position shown in Figure 3, to that shown in Figure 1, will free the cam surfaces 42-42 from the dog so as to permit the downward swinging movement thereof. Movement to the right of the pinion, as viewed in Figure 1, is finally limited by engagement of the hub sections thereof with the notched portions 44 of the faces 43 of the member G, whereupon further rotation of the operating shaft C and the pinion D will cause rotation of the gear B in a contra-clockwise direction, as viewed in Figure 1, to effect tightening of the brake chain on the chain winding drum, as hereinbefore described.

From the preceding description taken in connection with the drawing, it will be evident that I have provided an exceedingly simple and

efficient hand brake mechanism, wherein all the operations necessary to tighten and release the brakes are performed by rotation of the hand wheel in the proper direction, operation of the hand wheel in a direction to unwind the chain also releasing the locking dog of the brake mechanism so as to permit free running of the chain winding drum, and rotation of the hand wheel in a chain tightening direction restoring said dog to operative position to hold the chain winding drum against movement in an unwinding direction.

I have herein shown and described what I now consider the preferred manner of carrying out my invention, but the same is merely illustrative and I contemplate all changes and modifications that come within the scope of the claims appended hereto.

I claim:

20. 1. In a hand brake mechanism for railway cars, the combination with a chain tightening member operative in one direction to effect tightening of the brakes and in a reverse direction to effect release of the brakes; of means operatively connected to said tightening member for actuating the same; a locking dog for holding said tightening member against movement in releasing direction, said actuating means being bodily displaceable with respect to the dog to engage and actuate said dog to released position; and means for guiding said actuating means for limited bodily movement, operation of said actuating means in a direction to release the brakes effecting bodily movement in one direction thereof and actuating the dog to withdraw the same from operative engagement, and operation of said means in a direction to tighten the brakes effecting bodily displacement of the actuating means to said limited extent in a direction to free said dog and effect return thereof to holding position.

25. 2. In a hand brake mechanism, the combination with a rotary chain winding member; of rotary means for actuating said winding member, said rotary means and rotary member being bodily displaceable with respect to each other while operatively engaged; a locking dog cooperating with said winding member for preventing retrograde rotation thereof, bodily displacement in one direction of said rotary means displacing the dog by engagement therewith to disengage the same from said winding member and bodily displacement thereof in a reverse direction effecting return of the dog to operative position.

30. 3. In a hand brake mechanism, the combination with a rotary chain winding member; of rotary means for actuating said winding member, said rotary means being bodily displaceable to a limited extent with respect to the rotary member while in operative engagement therewith, said rotary member being bodily displaceable in one direction when actuated in a direction to effect unwinding of the chain and bodily displaceable in a reverse direction when actuated in a direction to effect winding of the chain; a locking dog cooperating with said winding member to hold the same against rotation in an unwinding direction, said dog being actuated by said rotary actuating means and disengaged from said winding member by bodily displacement of the actuating means in said first named direction and reengagement of the dog with the winding means being effected by

bodily displacement of said rotary means in said second named direction.

4. In a hand brake mechanism, the combination with a chain winding drum; of a driving gear operatively connected to said drum; a pinion for actuating said gear; guide means for guiding said pinion for limited bodily movement with respect to said gear, while in operative engagement therewith; a locking dog cooperating with said drum for preventing retrograde rotation thereof, rotation of said pinion in a direction to unwind the chain effecting bodily displacement of the pinion by engagement with the teeth of the gear in a direction to engage said dog and withdraw the same from operative relation to the chain winding drum, and rotation of said pinion in a chain winding direction effecting displacement thereof in a reverse direction, thereby releasing said dog and effecting restoration thereof to operative position, and also effecting return of the pinion to operative position to produce rotation of the winding drum in chain winding direction.

5. In a hand brake mechanism, the combination with a chain winding drum; of a gear operatively connected to the drum; a manually actuated rotary operating member; a locking dog for preventing retrograde rotation of said drum; a pinion fixed to said operating member and engaged with said gear; guide means for said rotary operating means for guiding the same for bodily movement with respect to said drum, said pinion and operating member being bodily displaced in one direction by the cooperating gear teeth of the pinion and gear to engage and actuate said dog, when said operating member is rotated in a direction to effect unwinding of the chain, and being bodily displaceable in a reverse direction when rotated in a direction to wind the chain, displacement in said first named direction retracting the dog from operative holding engagement with respect to the drum and maintaining the dog in said condition, and displacement in said second named direction effecting return of the dog to operative position, and further rotation of said pinion effecting operation of said drum in a chain winding direction.

6. In a hand brake mechanism, the combination with a rotary chain winding member; of a gear fixed to said member; a locking dog cooperating with said member for holding the same against movement in chain unwinding direction, said dog being retractable from holding position; means for retracting said dog and retaining the same in retracted position, said means being bodily reciprocable to actuate said dog to retract the same and also restore it to operative position, said means including a rotatable pinion meshing with said gear for reciprocating said means; and stop means for limiting the reciprocating movement of said means, whereby further rotation of the pinion causes rotation of the chain winding means.

7. In a hand brake for railway cars, the combination with a movable chain tightening member; of a locking dog cooperating with said member for holding the same against movement in chain releasing direction, said dog being retractable from holding position; rotary means which is also bodily reciprocable, said means being in one direction for retracting said dog and retaining the same in retracted position, and movable in a reverse direction for restoring the dog to operative position, said movable means

- being constantly operatively connected to the tightening member for rotating the same in reverse directions to respectively tighten and release the brakes.
5. In a hand brake for railway cars, the combination with a rotary chain winding drum; of a gear operatively connected to said drum; rotatable actuating means including a pinion; means for guiding said pinion for bodily reciprocating movement with respect to said gear; a locking dog cooperating with said winding drum for preventing retrograde rotation thereof, said dog being retracted by reciprocating movement of said pinion; and means for holding said pinion in position to maintain said dog retracted. 80
9. In a hand brake for railway cars, the combination with a rotary chain winding drum; of a gear operatively connected to said drum; rotatable actuating means including a pinion; means for guiding said pinion for bodily reciprocating movement with respect to said gear; a locking dog cooperating with said winding drum for preventing retrograde rotation thereof, said dog being retracted by reciprocating movement of said pinion; and gravity actuated means for holding said pinion in position to maintain said dog retracted. 85
10. In a hand brake for railway cars, the combination with a rotary chain winding drum; of a gear operatively connected to said drum; rotatable actuating means including a pinion; means for guiding said pinion for bodily reciprocating movement with respect to said gear; a locking dog cooperating with said winding drum for preventing retrograde rotation thereof, said dog being retracted by reciprocating movement of said pinion; and gravity actuated means for holding said pinion in position to maintain said dog retracted. 90
11. In a hand brake for railway cars, the combination with a rotary chain winding drum; of a gear operatively connected to said drum; rotatable actuating means including a pinion; means for guiding said pinion for bodily reciprocating movement with respect to said gear; a locking dog cooperating with said winding drum for preventing retrograde rotation thereof, said dog being retracted by reciprocating movement of said pinion; and means rendered operative by reciprocation of said pinion for moving said dog to fully retracted position. 100
12. In a hand brake for railway cars, the combination with a rotary chain winding drum; of a gear operatively connected to said drum; rotatable actuating means including a pinion; means for guiding said pinion for bodily reciprocating movement with respect to said gear; a locking dog cooperating with said winding drum for preventing retrograde rotation thereof, said dog being retracted by reciprocating movement of said pinion; and means rendered operative by reciprocation of said pinion for moving said dog to fully retracted position and latching said pinion against return reciprocating movement while said dog is retracted. 105
13. In a hand brake for railway cars, the combination with a rotary chain winding drum; of a gear operatively connected to said drum; rotatable actuating means including a pinion; means for guiding said pinion for bodily reciprocating movement with respect to said gear; a locking dog cooperating with said winding drum for preventing retrograde rotation thereof, said dog being retracted by reciprocating movement of said pinion; and means rendered operative by reciprocation of said pinion for moving said dog to fully retracted position and latching said pinion against return reciprocating movement while said dog is retracted, said pinion and last named means having engagement with each other, whereby rotation of the pinion in a direction to wind the chain effects release of said means from latching relation with respect to said pinion. 110
14. In a hand brake for railway cars, the combination with a rotary chain winding drum; of a gear fixed to said drum; a pinion fixed to said shaft and rotatable therewith; guide means for guiding said shaft for bodily movement with respect to said gear; a locking dog for preventing retrograde rotation of said winding drum, said dog being retractable from operative holding engagement with respect to said drum, said pinion through its engagement with the gear being moved along said guide means in one direction when rotated in chain winding direction and in reverse direction when rotated in unwinding direction, and engaging said dog when moved in said last named direction to withdraw the same from holding position, movement of said pinion in said first named direction effecting return of the dog to holding position. 115
15. In a hand brake for railway cars, the combination with a rotary chain winding drum; of a gear fixed to said drum and rotatable therewith; a rotary operating shaft; a pinion fixed to said shaft and rotatable therewith; guide means for guiding said shaft for bodily movement with respect to said gear; a locking dog for preventing retrograde rotation of said winding drum, said dog being retractable from operative holding engagement with respect to said drum, said shaft being reciprocated in said guide means upon rotation thereof in reverse directions through engagement of the pinion with said gear, said dog having cam means thereon cooperating with means on the pinion whereby the dog is actuated to be retracted from said gear when said shaft is reciprocated. 120
16. In a hand brake for railway cars, the combination with a rotary chain winding drum; of a gear fixed to said drum; a pinion meshing with said gear; a rotatable operating means including a shaft carrying said pinion; means for guiding said operating shaft for reciprocating movement; a gravity actuated locking dog for holding said drum against retrograde rotation, said dog being retractable from said holding position, said dog being engaged by said operating means and retracted upon movement of the latter in one direction along said guide means; and a pivoted latching member controlled by the reciprocation and rotation of the operating means for latching the latter in position to hold said dog retracted. 125
17. In a hand brake for railway cars, the combination with a rotary chain winding drum; of a gear fixed to said drum; a pinion meshing with said gear; a rotatable operating means including a shaft carrying said pinion; means for guiding said operating shaft for reciprocating movement; a gravity actuated locking dog for holding said drum against retrograde rotation, said dog being retractable from said holding position, said dog being engaged by said operating means and retracted upon displacement of the latter in one direction; and a pivoted latching member controlled by the reciprocation and rotation of the operating means for latching the latter in said displaced position, said latching member having cam means thereon cooperating with said dog to effect complete retraction of the same from said holding position. 130
18. In a hand brake for railway cars, the combination with a rotary chain winding drum; of a gear fixed to said drum; a pinion meshing with said gear; a rotatable operating means including a shaft carrying said pinion; means for guiding said operating shaft for reciprocating movement; a gravity actuated locking dog for holding said drum against retrograde rotation, 135
19. In a hand brake for railway cars, the combination with a rotary chain winding drum; of a gear fixed to said drum; a pinion meshing with said gear; a rotatable operating means including a shaft carrying said pinion; means for guiding said operating shaft for reciprocating movement; a gravity actuated locking dog for holding said drum against retrograde rotation, 140
20. In a hand brake for railway cars, the combination with a rotary chain winding drum; of a gear fixed to said drum; a pinion meshing with said gear; a rotatable operating means including a shaft carrying said pinion; means for guiding said operating shaft for reciprocating movement; a gravity actuated locking dog for holding said drum against retrograde rotation, 145
21. In a hand brake for railway cars, the combination with a rotary chain winding drum; of a gear fixed to said drum; a pinion meshing with said gear; a rotatable operating means including a shaft carrying said pinion; means for guiding said operating shaft for reciprocating movement; a gravity actuated locking dog for holding said drum against retrograde rotation, 150

said dog being retractable from said holding position, said dog being engaged by said operating means and retracted upon displacement of the latter in one direction; and a pivoted latching member controlled by the reciproca-
5 tion and rotation of the operating means for latching the latter in said displaced position, said latching member having cam means thereon cooperating with said dog to effect complete retraction of the same from said holding position, said rotatable operating means and latching member having camming engagement with each other for effecting restoration of said latch member when said operating means is rotated in chain winding direction.
10 15

18. In a hand brake mechanism, the combination with a rotary chain-winding element; of

releasable holding means for preventing rotation of said element in unwinding direction; a driving gear operatively connected to said element; a rotary pinion constantly meshing with said gear and rotatable in one direction while in constant engagement with the gear for actuating the gear to rotate said element in chain-winding direction; and means automatically thrown into operation by rotation of said pinion in a reverse direction for releasing said holding means by withdrawing the same from operative position to permit rotation of said element in chain-unwinding direction, rotation of said pinion in said first named direction operating said second named means to effect restoration of the holding means to holding position.
